7 Claims. (Cl. 60—53)

ABSTRACT OF THE DISCLOSURE

A hydraulic drive including a pump and variable displacement motor incorporating a speed-responsive drive ratio control valve movable against a spring to increase the motor capacity and including means responsive to increase in torque being transmitted to decrease the force effect of the spring to control drive ratio as a function both of speed of rotation of the pump housing and torque being transmitted.

Specification

An object of this invention is to provide a drive mechanism wherein the drive ratio is controlled both as a function of speed of rotation of the output member and torque being transmitted by the output member.

Another object of this invention is to provide in a drive mechanism a drive ratio control valve controlled as a function of speed of rotation of the valve and the torque being transmitted by the drive mechanism.

A further object of this invention is to provide a drive mechanism incorporating a pump and motor having a variable displacement wherein the motor displacement is controlled as a function of speed of rotation of a pump element and as a function of torque loading of the pump element.

A more specific object of this invention is to provide in a drive mechanism of the type described a speed-responsive valve movable against a biasing means to increase the motor capacity together with torque-responsive means effective with increase in torque being transmitted to decrease the effect of the valve biasing means to permit change of drive ratio as a function of both speed of rotation of the pump housing and torque being transmitted through the pump housing.

A more specific object of this invention is to provide in a drive structure of the type described a speed-responsive valve movable against a spring to increase the pump capacity together with torque-responsive means responsive to increase in torque to move a valve seat to decrease the effective force of the valve spring and conversely, movable upon decrease in torque to increase the force effect of the valve spring upon the speed-responsive valve.

These and other objects and advantages of this invention will be apparent from the following description and claims taken in conjunction with the accompanying drawings in which:

FIGURE 1 is a longitudinal sectional view of a drive structure constructed in accordance with the principles of this invention;

FIGURE 2 is an elevational view taken along the line 2—2 of FIGURE 1; and

FIGURE 3 is a set of curves illustrating the representative torque requirement in relation to input speed, the operation wherein the control valve is solely speed-responsive, and the operation of the present invention wherein the valve is both speed and torque controlled.

Referring to FIGURE 1 there is shown a drive mechanism constructed in accordance with the principles of this invention. The drive unit includes a constant displace-

ment pump indicated generally by the number 10 and a hydraulic motor indicated generally by the number 7. Pump 10 is a vane-type pump including a rotor 11, vanes 12 and a cam ring 13. Passages 14 extend through rotor 11 adjacent the inner ends of the vanes for urging the vanes outwardly against cam ring 13 with fluid pressure to assist centrifugal force during rotor rotation. A two-part pump housing 15, 16 encloses the vane rotor and cam ring, being pinned to cam ring 13 by pins 17 and is secured together by studs 18. A pressure plate 19 is disposed between rotor 11 and housing section 16. A spring 20 biases pressure plate 19 and rotor 11 axially against housing section 15. Rotor 11 is splined at 9 to an engine driven crank shaft 8 such that pump rotor 11 will be driven at engine speed whenever the engine (not shown) is operated.

A hub 21 extends axially from housing part 15 and is coupled directly to a rotor of motor 7 having two parts 22, 23. The rotor carries slidable vanes 24 which operate a circular cam ring 25. A motor housing 26 which is fixed against rotation by any suitable means, as by bolting to the engine (not shown), encloses the motor. A plate 27 closes off the end of the housing 26 adjacent the engine and is retained on housing 26 by a snap ring 28. A pressure plate 29 disposed between the motor rotor and end plate 27 is slidable axially and functions as a piston for biasing the two part rotor 22, 23 against the web of the motor housing 26. A pin 30 carried by pressure plate 29 extends into a recess 31 in cam ring 25 and a pin 32 pins pressure plate 29 to housing 26. Cam ring 25 is thus permitted radial travel but is anchored against rotation. The displacement of the motor may be varied by changing the radial position of cam ring 25. A spring 33 biases cam ring 25 towards its position shown, concentric with the motor rotor and power input shaft 8.

A spring seat 34 screw-threaded in the motor housing may be rotated relative to the housing to adjust the compressive force of spring 33. A fluid pressure-responsive bellows 35 is positioned between cam ring 25 and housing 26, diametrically opposite spring 33 for moving cam ring 25 eccentrically of the motor rotor to increase the fluid displacement of the motor. Passages 36 in the motor rotor admit pressure beneath motor vanes 24 for biasing them outwardly against cam ring 25.

Between pump pressure plate 19 and pump housing portion 16 is a reservoir 40 for fluid which is circulated through the pump and motor and which is used to actuate bellows 35. Fluid inlet to the pump is through two diametrically shaped grooves 42 in the rotor side of pressure plate 19 and connected to reservoir 40 by passage 41 in the pressure plate. Circumferentially spaced from each inlet pocket 42, and on the opposite side of the pump rotor, is the pump outlet in the form of two diametrically spaced pockets 43 in the housing part 15. Connecting passages 44, 45, 46, and 47 extend through housing part 15, motor rotor parts 22, 23 and motor pressure plate 29, respectively, to connect pump pockets 43 with an annular chamber 48 between pressure plate 29 and end plate 27 of the motor. Fluid pressure thus delivered to chamber 48 from the pump during operation causes pressure plate 29 to bias the motor rotor against the web of motor housing 26. The inlet to the motor is in the form of a plurality of circumferentially spaced pockets (one shown at 49) on the rotor side of the motor pressure plate 29 and these pockets are connected with the annular space 48 by passages 50 through pressure plate 29. The outlet for the motor is in the form of an equal number of circumferentially spaced pockets in the web of the motor housing 26, one being shown at 51. Additional passages 52 in the motor housing and a passage 53 in the pump housing part 15 connect to passage 64 through the pump rotor and

these passages 64 connect with passages 39 through pump pressure plate 19 leading back to reservoir 40.

Oil or other fluid may be used as the working fluid, and is pumped to the motor and returned to the pump reservoir in response to relative rotation of the engine crankshaft and housing 15-16. When the fluid displacement of the motor is zero, that is when the motor cam ring 25 is concentric with the rotor 22, 23, all reaction from the pump pressure is taken directly by the pump cam ring 13 and applied by it to the pump housing 15-16 such that the speed of rotation of the pump housing is driven at a speed having a constant ratio to crankshaft speed. As the fluid displacement of the motor increases by shifting its cam ring 25 eccentrically of the motor rotor, less of the pump pressure reaction is taken directly by pump cam ring 13, and is instead applied against the rotor 22, 23 of the motor in effecting its rotation as a result of the pump pressure delivered to the chamber 55 of the motor between the vaned motor rotor 22, 23 and the motor cam ring 25.

Actuation of bellows 35 to effect such eccentric positioning of motor cam ring 25 is accomplished by applying hydraulic pressure from the pump for expanding bellows 35. Passage means for expanding bellows 35 includes a pocket 56 in the motor housing wall communicating with the interior of bellows 35, passages 57, 58, 59, 60 and 61 provided in motor pressure plate 29, rotor parts 22, 23, and pump housing parts 15, 16. Between passage 61 and reservoir chamber 40 is a connecting passage 62 in the form of a bore of a valve body 63 formed integral with pump housing part 15. Bore 62 extends radially of the unit and receives a slidably centrally apertured valve 64. In the position shown valve 64 closes passage 61 against the application of fluid pressure from reservoir 40 to bellows 35. A spring 65 biases valve 64 toward its closed position and is seated upon a plug 70 threaded into valve body 63. It will be apparent that valve 64 is centrifugally force-responsive and that at speeds below a predetermined speed of rotation will close off passage 61. By selecting a spring 65 of sufficient stiffness the valve can be maintained in its closed position against the centrifugal force induced by rotation of the pump housing at speeds thereof below a predetermined speed at which it is desired to open.

Fixed to pump housing part 16 for rotation therewith is a pulley drive member 75 providing a seat for a resilient member 76 which carries a pulley sheave 77. More specifically, pulley sheave 77 is connected to pump housing portion 16 by a resilient connector 76. Member 77 is illustrated as an annular ring having rubber-like characteristics and bonded to drive member 75 and the base of driven pulley sheave 77. Pulley sheave portion 77 drives a belt 78 which may drive the accessories of a vehicle engine such as the fan, generator, power steering pump or air-conditioning compressor, and which is therefore subjected to variation in load depending upon the number of units being operated at any given time and the speed of operation of such units. A rack 80 carried by pulley sheave 77 mates with a pinion 81 formed on valve seat plug 70. It will be apparent that due to the loading applied to belt 78 and sheave 77 that resilient member 76 through which torque is transmitted from member 75 to pulley sheave 77 will accommodate limited angular rotation of pulley sheave 77 relative to pump housing part 16. As the pulley load is increased the rack and pinion rotates plug 70 relative to the pump housing such that the force effect of spring 65 on valve 64 is decreased. In this manner the preload of spring 65 is adjusted by torsional rotation of output drive pulley 77 such that increase of torque rotates the preload plug adjuster 70 to decrease the preload on spring 65 which thereby reduces the output speed of the pump housing 15, 16 and pulley 77. The device functions to produce a constant power drive by decreasing the output speed as the torque being transmitted increases and by increasing the output speed as the torque being trans-

mitted decreases. A constant power drive mechanism as described will permit running of a prime mover at constant speed and will still produce variable output torque on an as-required basis adjusting the output speed correspondingly such that the product of speed and torque will balance the input power to the drive mechanism.

To more particularly explain the invention, there is shown in FIGURE 3 three curves A, B, C. Curve A is a curve illustrating input speed, output speed and a representative torque requirement in relation to output speed for a pulley driven at a fixed ratio relative to input speed. Curve B is a curve illustrating the operation of a device wherein the preload of spring 65 is constant and valve 64 is solely speed responsive to open at a predetermined speed of rotation of the pump housing. Curve C represents the operation of the present invention wherein the output speed of rotation of the pump housing is controlled to reduce the output speed in response to increase in torque loading. In the arrangement of curve B wherein the valve 64 would be solely centrifugally operated the valve has a linear displacement as a function of speed. In the present invention the displacement of valve 64 is a non-linear displacement corresponding to the output torque of the drive mechanism.

Assuming that valve 64 should open to meter sufficient pressure to expand bellows 35, cam ring 25 will move against spring 65 and be positioned in eccentric relationship with respect to the rotor axis and the motor rotor is caused to rotate. Since the motor rotor is fixed for rotation with pump housing part 15, there is a "feedback" of torque to the pump housing to assist in driving the accessories. The output torque is split between that directly imparted to the pump cam ring and housing as a result of reaction to fluid pressure developed in the pump pumping chamber and that imparted to the pump housing, resulting from drive of the pump housing by the motor rotor 22, 23. Valve 64 is both speed responsive and torque responsive. An increase in speed of rotation of valve 64 results in increase in centrifugal force acting on valve 64 tending to open the valve against spring 65 to admit fluid to bellows 35 to increase the eccentricity of the motor cam ring 25. As this eccentricity increases, the fluid displacement of the motor increases with the result that an increasing share of the input torque from crankshaft 8 is transmitted to the pump housing and pulley 77 via the motor. Insofar as the speed response of valve 64 is concerned the motor thus serves to an increasing extent with increased crankshaft speed as a by-pass for the pump such that the drive ratio between the crankshaft 8 and pulley 77 decreases from unity. Insofar as the torque response is concerned, an increase in the load driven by pulley sheave 77 will cause limited angular rotation of pulley sheave 77 relative to the pump housing whereupon the rack 80 and pinion 81 rotate valve plug seat 70 in a valve body 63 to decrease the preload of spring 65. Such rotation of spring seat 70 decreases the force effect of spring 65 to permit a further movement of valve 64 against spring 65 (for a given speed of rotation of the pump housing) such that the by-pass effect of the motor is increased and the speed of rotation of the pump housing decreases relative to increase in crankshaft speed to a greater extent than is true in structures wherein valve 64 is solely speed responsive. This additional control, wherein an increase in torque being transmitted through belt 78 modifies the action of valve 64, may be calibrated such that the power being delivered to belt 78 which is the product of torque times speed may be constant irrespective of variation of speed of rotation of crankshaft 8. By weakening the force effect of spring 65 in response to increase in torque being transmitted the centrifugal force acting on valve 64 is rendered more effective on valve 64 for a given speed of rotation, and conversely, if the torque being transmitted at a given speed of rotation is decreased, relative angular rotation of pulley sheave 77 relative to the pump housing will cause valve seat plug 70 to rotate relative to the

pump housing to increase the force effect of spring 65 to provide increased resistance to centrifugal force acting on valve 64, to speed up the speed of rotation of pulley 77 relative to crankshaft speed for a given speed of rotation of shaft 8. In this manner the power transmitted which is the product of speed and torque may be made constant irrespective of variation of speed of rotation of shaft 8.

What is claimed is:

1. In a variable ratio drive, a power input shaft, a pump, a motor, a pump rotor driven by said shaft, a pump reaction member, a pump housing adapted to be driven by said pump reaction member, a motor housing fixed against rotation, a motor rotor fixed for rotation as a unit with said pump housing, a pump reaction member capable of radial movement with respect to said motor rotor, means biasing said pump reaction member into concentric relationship with respect to said motor rotor, fluid pressure responsive means adapted to move said motor reaction member into eccentric relationship with respect to said motor rotor, a reservoir in said pump housing, passage means for delivering fluid pressure from said pump to said motor rotor and for returning fluid from said motor to said pump reservoir, additional passage means between said reservoir and said fluid pressure-responsive means, a valve for controlling said additional passage means, biasing means for positioning said valve to block off said additional passage means, said valve being movable in response to centrifugal force upon rotation of said pump housing, a power delivery member driven by said pump housing, and means responsive to torque being transmitted by said power delivery member for varying the force effect of said valve biasing means in response to variation of torque being transmitted by said power delivery member.

2. A variable ratio drive as set forth in claim 1 wherein said valve biasing means comprises a spring and said means for varying the force effect of said valve biasing means includes a spring seat carried by said pump housing and movable relative to said pump housing in response to variation of torque being transmitted by said power delivery member.

3. A variable ratio drive according to claim 1 wherein said valve is movable in response to centrifugal force to open said additional passage, wherein said valve biasing means includes a spring seated upon a spring seat rotatable in said pump housing and movable radially with respect to said valve upon rotation relative to said pump housing, and wherein said torque-responsive means is operatively connected to said spring seat for rotating said spring seat relative to said pump housing.

4. A variable ratio drive as set forth in claim 1 wherein said valve is responsive to centrifugal force upon rotation of said pump housing to open said additional passage means, said valve biasing means comprises a spring seated upon a spring seat adapted upon rotation to move radially with respect to said valve and wherein said power delivery member is driven from said pump housing by a resilient connection to said housing permitting limited angular rotation of said power delivery member with respect to said housing, and means operatively connecting said power delivery member to said spring seat for rotating said spring seat in response to angular rotation of said power delivery member with respect to said pump housing.

5. In a variable ratio drive, a rotatable pump housing enclosing a pump rotor, a pump reaction member fixed for rotation with said housing, a power input shaft for driving said rotor, a fluid reservoir in said pump, a motor having a housing fixed against rotation, a rotor fixed for rotation as a unit with said pump housing, a motor reaction member radially movable with respect to said motor rotor, working fluid in said reservoir, passage means

for delivering fluid from said pump to said motor for driving said motor and for returning fluid to said reservoir, means biasing said motor reaction member into concentric relationship with respect to said motor rotor, fluid pressure-responsive means for moving said motor rotor, into eccentric relationship with respect to said motor rotor, additional passage means between said pump reservoir and said fluid pressure-responsive means, a valve carried by said pump housing for controlling said additional passage means, spring means yieldably biasing said valve to block off said additional passage means from said reservoir, said valve being responsive to centrifugal force in response to rotation of said pump housing to open said additional passage means to said reservoir, a valve seat for said spring means screw threaded into said pump housing and adapted to be rotated to vary the force effect of said spring means, a final power delivery member, a resilient drive connection between said pump housing and final delivery member permitting limited angular rotation of said final drive member with respect to said pump housing in response to variation of torque being transmitted by said final drive member, a rack fixed to said final drive member, and a pinion rotatable as a unit with said valve seat and mating with said rack, said rack and pinion being effective upon increase of torque being transmitted by said final output member to rotate said valve seat to reduce the force effect of said spring means and effective upon decrease of torque being transmitted to increase the force effect of said spring means.

6. In a variable ratio drive, a pump including a rotatable pump housing, a pump rotor, a reaction member fixed for rotation with said pump housing and adapted to drive said housing in response to rotation of said rotor, a power input shaft for driving said pump rotor, a motor having a housing fixed against rotation, a vane rotor having vanes radially movable with respect to said rotor, a cam ring contacting said vanes and radially movable with respect to said motor rotor, said motor rotor being connected for rotation as a unit with said pump housing, a fluid reservoir in said pump housing, passage means for delivering fluid from said pump to said motor and for returning fluid from said motor to said reservoir, spring means yieldably biasing said motor cam ring into concentric relationship with respect to said motor rotor, fluid pressure-responsive means adapted to move said motor cam ring into eccentric relationship with respect to said motor rotor, a control passage between said fluid pressure-responsive means and said reservoir, a centrifugal force-responsive valve in said pump housing for controlling fluid flow through said control passage, a spring yieldably biasing said valve to block off said control passage, a spring seat movable relative to said pump housing for varying the force effect of said spring, a power delivery member, resilient means for driving said power delivery member from said pump housing and accommodating limited angular rotation of said power delivery member with respect to said housing, and additional means connecting said power delivery member to said spring seat for decreasing the force effect of said spring in response to increase in torque transmitted to said power delivery member, and for increasing the force effect of said spring in response to a drop of torque transmitted by said power delivery member.

7. A drive structure according to claim 6 wherein said spring seat is moved in response to variation in torque demand to maintain constant power output irrespective of variation of speed of rotation of said input shaft.
